ABSTRACT

The relief from poison ivy on warm-blooded animals is obtained by applying to the surface of the affected area, a tetraalkyl diamide of the formula:

wherein each R represents a member selected from the group consisting of a saturated aliphatic hydrocarbon group of from 1 to 6 carbon atoms and an unsaturated aliphatic hydrocarbon group of from 1 to 6 carbon atoms, and wherein R₁ represents a member selected from the group consisting of a saturated aliphatic hydrocarbon group of from 0 to 22 carbon atoms and an unsaturated aliphatic hydrocarbon group of from 0 to 22 carbon atoms.

11 Claims, No Drawings

- N,N-dimethylamide-N',N'-dibutylamide of adipic acid
 N,N-dimethyl-N',N'-dihexyldiamide of pimelic acid
 N,N,N',N'-tetraisopropylsuccinamide of azelaic acid
 N,N-dimethyl-N',N'-dihexyldiamide of azelaic acid
 N,N,N',N'-tetraallyldiamide of azelaic acid
 N,N-di-n-butyl-N',N'-dihexyldiamide of sebamic acid
 N,N,N',N'-tetramethyldiamide of iso-sebamic acid
 N,N,N',N'-tetraisopropylsuccinamide of brassylic acid

The compounds of this invention may be prepared according to the established synthesis procedure set forth in U.S. Pat. No. 3,417,114 and/or U.S. Pat. No. 3,288,794, the subject matter of which, insofar as it pertains to the preparation of such compounds, is incorporated herein by reference.

The tetraalkyl diamides of this invention are preferably applied as a solution (normally, 1-95%, but preferably 5-25%) in water. The term "solution" is meant to include a water-miscible alcohol solution, such as isopropyl alcohol or ethyl alcohol, or the alcohol may be used undiluted. The solution is applied in any suitable manner, e.g., by spraying or swabbing the dermatitic area. Alternatively, the tetraalkyl diamides of this invention may be applied in the form of any other topical pharmaceutical form, such as a powder, paste, salve, ointment, aerosol spray, etc. These compounds can also be dissolved in a cosmetic base, a cream or oil, and added to other solutions or sprays normally applied to the skin, such as insect repellants, sun screen lotions, and ointments and creams normally used in the treatment of skin rashes and allergies, and in topical anesthetics used for the relief of pain and itching of sunburn. The skilled artisan concerned with the subject matter of this invention can easily prepare any of the above-mentioned conventional pharmaceutical dosage forms for topical application by simply referring to "REMINGTON'S PHARMACEUTICAL SCIENCES" (Fourteenth Edition), 1970, pp. 1461-1762.

Normally, a single application brings immediate relief to the area treated; however, for stubborn cases, repeated application may be necessary.

Without further elaboration, it is believed that one of ordinary skill in the art can, using the preceding description, utilize the present invention to its fullest extent. The following preferred specific embodiments are, therefore, to be construed as merely illustrative, and not limitative of the remainder of the specification and claims in any way whatsoever.

EXAMPLE I

Set forth below are some illustrative topical formulations containing a selected tetraalkyldiamide compound of the instant invention.

Formulation Number 1 — Solution

N,N,N',N'-tetramethyl succinamide 1 - 25%
 Distilled water qs to 100%

Procedure: Dissolve the tetramethyl succinamide in enough water to make 100%. Filter the solution. Apply to the effected area.

Formulation Number 2 — Tincture

N,N,N',N'-tetramethyl succinamide 1
 Alcohol USP 25%
 Water qs 50%
 100%

Procedure: Dissolve the tetramethyl succinamide in the alcohol. Add sufficient water to make 100%. Filter and apply to affected area.

Formulation Number 3 — Topical Aerosol

N,N,N',N'-tetramethyl succinamide 1	25%
Alcohol USP	5%
Isopropylmyristate	5%

*Conventional halogenated hydrocarbon propellant qs 100%
 e.g. - Freon 11 (trichlorofluoromethane), Freon 12 (dichlorodifluoromethane), Freon 14 (carbon tetrafluoride), Freon C 318 (Octafluorocyclobutane), Freon 114 (Cryofluorane), etc.

Procedure: Dissolve the tetramethyl succinamide in the alcohol and isopropylmyristate. Add sufficient halogenated propellant and introduce into conventional aerosol containers either by pressure or by cold filling. Apply to affected area.

Formulation Number 4 — Ointment

N,N,N',N'-tetramethyl succinamide 1	25%
Petrolatum USP qs	100%

Procedure: Heat the petrolatum to 60° C. Add the tetramethyl succinamide and stir until thoroughly dispersed. Cool to room temperature. Apply to affected area.

The concentrations implied in the above exemplary formulations are typical of those used medicinally but in no way should they be construed as limiting the scope of this invention.

EXAMPLE II

(In Vivo Studies)

A topical aerosol formulation, in accordance with Formulation Number 3 of Example I above was prepared. The concentration of tetramethylsuccinamide in the formulation was 5 percent. The halogenated hydrocarbon propellant employed was a conventional propellant, *Freon 11-12 (50/50). *A 50/50 mixture of Freon 11 and Freon 12.

At 24 hour intervals, the aerosol was applied to dermatitic areas resulting from poison ivy contact on human volunteers of both sexes. Within 24 to 36 hours following application, dramatic reduction in the dermatitis of each individual treated was observed.

The tetraalkyl diamide compounds of this invention are highly water soluble and a finite affinity for the organic phase. These characteristics permit dermal penetration without significant systemic absorption. In addition, the topical LD₅₀ of these compounds is relatively high. For instance, the compound, N,N,N',N'-tetramethyl succinamide gave a topical LD₅₀ of 2000 mg./Kg. when applied to denuded rabbits.

From the foregoing description, one skilled in the art can easily ascertain the essential characteristics of this invention, and without departing from the spirit and scope thereof, can make various changes and modifications of the invention to adapt it to various usages and conditions. Thus, such changes and modifications are properly, equitably and intended to be, within the full range of equivalence for the following claims.

What I claim is:

1. A method of reducing poison ivy dermatitis on a warm-blooded animal, which comprises applying to the dermatitic area, an effective amount of a compound of the formula:

wherein each R represents a member selected from the group consisting of a saturated aliphatic hydrocarbon group of from 1 to 6 carbon atoms and an unsaturated aliphatic hydrocarbon group of from 1 to 6 carbon atoms, and wherein R₁ represents a member selected from the group consisting of a saturated aliphatic hydrocarbon group of from 0 to 22 carbon atoms and an unsaturated aliphatic hydrocarbon group of from 0 to 22 carbon atoms,

whereby said compound forms a molecular complex with urushiol, the causative agent of said dermatitis.

2. The method of claim 1, wherein said compound is: N,N,N',N'-tetramethyl adipamide.

3. The method of claim 1, wherein said compound is:

N,N,N',N'-tetramethylglutaramide.

4. The method of claim 1, wherein said compound is: N,N,N',N'-tetramethylsebacamide.

5. The method of claim 1, wherein said compound is: N,N,N',N'-tetramethylsuccinamide.

6. The method of claim 1, in which said compound is applied as a pharmaceutically acceptable topical preparation.

7. The method of claim 2, wherein said compound is applied as a water solution.

8. The method of claim 2, wherein said compound is applied as an alcohol solution.

9. The method of claim 2, wherein said compound is applied as an aqueous-alcoholic solution.

15 10. The method of claim 2, wherein said compound is applied as a halogenated hydrocarbon propellant solution.

11. The method of claim 10, wherein said propellant is a 50/50 mixture of trichlorofluoromethane and di-20 chlorodifluoromethane.

UNITED STATES PATENT OFFICE
CERTIFICATE OF CORRECTION

Patent No. 3,875,301

Dated April 1, 1975

Inventor(s) John J. Windheuser

It is certified that error appears in the above-identified patent and that said Letters Patent are hereby corrected as shown below:

IN THE TITLE:

Delete "DIAMINES" and insert --DIAMIDES--.

IN THE SPECIFICATION:

Column 3, the first line following the heading "Formulation Number 2 - Tincture" delete "1"; delete "25%" and insert -- 1 - 25% --.

Column 4, the first line following the heading "Formulation Number 3 - Topical Aerosol" delete "1"; delete "25%" and insert -- 1 - 25% --.

Column 4, the first line following the heading "Formulation Number 4 - Ointment" delete "1"; delete "25%" and insert -- 1 - 25% --.
